UNITED STATES PATENT OFFICE.

FRANK W. WILLIAMS, OF CHICAGO, ILLINOIS.

TALKING-MACHINE NEEDLE.

1,344,839.

Specification of Letters Patent. Patented June 29, 1920.

Application filed August 21, 1917. Serial No. 187,468.

To all whom it may concern:

Be it known that I, FRANK W. WILLIAMS, a citizen of the United States, and a resident of the city of Chicago, in the county of Cook 5 and State of Illinois, have invented certain new and useful Improvements in Talking-Machine Needles; and I do hereby declare that the following is a full, clear, and exact description of the same, reference being had 10 to the accompanying drawings, and to the numerals of reference marked thereon, which form a part of this specification.

This invention relates to an improved form of a talking machine needle or stylus 15 member formed to permit either end of the needle thereof to be used as the playing point by simply reversing the needle tubing through which the needle member longitudinally projects.

It is an object of this invention to construct a phonograph playing needle both ends of which are adapted to be used as playing points.

It is furthermore an object of this invention to provide a needle tubing through which projects a needle having one of its extending ends longer than the other and further adapted to utilize either projecting end as the playing point.

It is an important object of this invention to provide a talking machine needle member of simple construction wherein a grooved longitudinally passaged supporting member has a needle projecting through said passage 35 to permit either end of the needle to be used as the playing point.

Other and further important objects of this invention will be apparent from the disclosures in the drawings and specification.

The invention (in a preferred form) is 40 illustrated in the drawings and hereinafter more fully described.

On the drawings:

Figure 1 is a fragmentary side elevational 45 view of the reproducing mechanisms of a phonograph the stylus bar of which supports a stylus or needle member embodying the principles of this invention.

Fig. 2 is a plan view of the phonograph 50 needle member.

Fig. 3 is a section taken on line 3—3 of Fig. 2, with the needle proper shown in elevation.

Fig. 4 is a section taken on line 4—4 of 55 Fig. 3.

Fig. 5 is a section similar to that shown

in Fig. 3, of a modified form of the device.

Fig. 6 is a longitudinal section of another modified form of the needle member. 60

As shown on the drawings:

The reference numeral 1, indicates a record carrying disk of a talking machine, having placed thereon a record 2. Mounted above the record and disk in any suitable manner is a sound reproducing mechanism comprising a sound box 3, to the top of which is attached a sound tube 4, which connects with the inner end of a megaphone or horn 5. Secured to the sound box 3, is a stylus bar 6, provided with a longitudinally passaged cylindrical stylus holder 7, having a threaded aperture in one side thereof to permit a headed set screw 8, to thread therethrough and removably engage in a peripheral groove formed by the neck 9, of a sound reproducing stylus or needle member embodying the principles of this invention. Said needle member comprises a short piece of tubing or casing comprising cylindrical portions 10 and 10^a and a neck 9 of reduced diameter integrally connecting said cylindrical portion. The diameter of the passage through said casing being small to permit a needle 11, to project centrally and longitudinally therethrough so that one projecting end 12, of said needle is longer than the other projecting end 13, to afford a means for reproducing softer or shriller tones depending upon whether the longer or shorter 80 end of the needle is used as the playing point. The neck 9, of the needle casing 10, is formed between the ends thereof and affords a means in which the inner end of the set screw 8, may seat to securely but removably hold the needle casing in position within the holder 7, of the stylus bar. 85

The operation and mounting of the needle mechanism is believed to be self evident. Either projecting end of the needle 11, is adapted to be used as the playing point independently of the other end by merely releasing the set screw 8, pulling out the needle casing 10, inverting the same and mounting the same in the needle holder 7, in said inverted position. The needle 11, and the casing 10, may of course be made of steel, brass or any other suitable material. 105

In the modified form of stylus or needle member shown in Fig. 5, the reference numeral 14, designates a tubing or casing, having a passage or opening formed centrally 110

and longitudinally therein. Secured in and projecting through the passage in said tubing 14, is a stylus or needle 15, the ends of which project beyond the ends of the tubing 14 to permit either of said ends to be used as the playing point. Threaded upon the tubing 14, or rigidly secured thereon by any other suitable means is a ring flange or collar 16, adapted to limit the inward movement of the tubing 14, into the needle holder 7, of the stylus bar 6. The tubing 14, is held secured in position by means of the retaining screw 8, which engages the portion of the tubing which projects into the holder 7.

Fig. 6, shows another modified form of the device comprising a casing or body portion 17, having integrally formed thereon between the ends thereof a ring flange or collar 18. Each end of the casing 17, is drilled axially to permit a needle 19, to be securely seated therein to permit the outer projecting end of either one of said needles to be used as the playing point. The needle casing 17, is adapted to be mounted with either end thereof projecting into the holder 7, the flange 18, acting to limit the inward movement of said casing. The retaining screw 8, is adapted to hold the casing 17, in position to permit the needle 19, secured in the other or outer end of the casing to be used as the playing point. As clearly shown in the drawings, the neck 9, and the flanges 16

and 18, respectively of the various forms of the device, are positioned at different distances from the ends of the respective needle casings thereby providing one end which is longer than the other whereby softer or louder sounds are produced depending upon whether the shorter or longer portion of the 40 needle member projects from the holder.

I am aware that various details of construction may be varied through a wide range without departing from the principles of this invention, and I therefore do not 45 purpose limiting the patent granted otherwise than necessitated by the prior art.

I claim as my invention:

1. A stylus for talking machines comprising a double pointed needle inclosed in a 50 casing with only the two points thereof projecting, said points being of unequal length so as to produce either a loud or soft tone.

2. A talking machine stylus comprising a casing adapted to be secured in the stylus 55 holder of a machine, said casing inclosing a needle with its two points projecting unequal distances therefrom.

In testimony whereof I have hereunto subscribed my name in the presence of two sub- 60 scribing witnesses.

FRANK W. WILLIAMS.
